[57] ABSTRACT

An apparatus for subjecting moving material to a liquid treatment, including a treatment zone defined in part by spaced opposed non-parallel wall members lying in planes which converge at a location exterior of the treatment zone. A flexible reed member extends into the treatment zone from support means located at said exterior location. Both the material being treated and the processing liquid are passed through the treatment zone, with the position of the reed member being such that the flow of processing liquid causes the reed member to vibrate laterally between the non-parallel wall members.

WET PROCESSING APPARATUS

BACKGROUND OF THE INVENTION

This invention relates generally to apparatus for subjecting moving material, usually in web form, to a wet treatment, and is particularly concerned with an improvement to apparatus of the type described in United States Letters Patent No. 3,430,466.

The aforesaid prior art apparatus includes a treatment zone defined in part by spaced opposed parallel wall members. Both the material to be treated and the treatment liquid are passed through the treatment zone. A flexible reed member which extends into the treatment zone from an exterior support, is caused to vibrate between the parallel wall members by the action of the liquid stream. Although this arrangement has operated in a generally satisfactory manner, several problems have been encountered. One such problem relates to the marking of delicate fabrics by the reed member as the latter vibrates between the parallel wall members. It is believed that this problem results from the fabric being pinched between the walls of the treatment zone and the upper edge of the vibrating reed member. Another problem relates to the premature failure of the vibrating reed member due to the development of metal fatigue.

SUMMARY OF THE INVENTION

A general object of the present invention is the provision of a novel and improved apparatus which obviates each of the above-mentioned problems. A more specific object of the present invention is to eliminate fabric marking by altering the relationship of the wall members forming the treatment zone and the reed member so as to avoid edge or line contact between the reed member and the fabric being treated. This is accomplished by arranging the wall members in non-parallel planes which converge at a location exterior of the treatment zone, and by supporting the reed member at said exterior location for vibrating motion about the line of convergence of said planes.

Another more specific object of the present invention is to provide an improved mounting means for the vibrating reed member, which means greatly prolongs the useful life of the reed member. This is accomplished by allowing the reed member to vibrate about one edge which is seated in a groove in a stationary support member, and by laterally supporting the reed member with resilient material.

BRIEF DESCRIPTION OF THE DRAWINGS

FIG. 1 is a view in side elevation with portions broken away of an apparatus embodying the concepts of the present invention; and,

FIG. 2 is an enlarged sectional view of the treatment zone, vibrating reed member and mounting means therefor.

Referring initially to FIG. 1, there is shown an apparatus 10 for washing textile material in web form. The apparatus includes a tank 12 containing the washing liquid 14. A housing 16 is mounted on the tank 12. The housing encloses a treatment chamber 18 which communicates with the underlying interior of the tank 12 via a treatment zone generally indicated at 20. A vibrating reed member 22 extends upwardly into the treatment zone 20 from a support means 24. The textile web 26 is threaded through a series of upper and lower

guide rolls 28a and 28b before passing upwardly through the treatment zone 20 into the treatment chamber 18. After entering the treatment chamber, the web material passes over another guide roller 30 and then continues downwardly back through the treatment zone 20 around another lower guide roll 32 before exiting upwardly over still another guide roll 34.

A pump 36 is located exterior of the tank 12 and is driven by a motor 38. Pump 36 has a suction line 40 communicating with the interior of tank 12 beneath the level of the washing liquid 14, and a discharge line 42 which connects the pump with the treatment chamber 18. Operation of the pump 36 results in liquid being pumped from tank 12 into the treatment chamber 18, from whence the liquid escapes in a manner indicated diagrammatically by the arrows in FIG. 1, downwardly through treatment zone 20 back to the tank 12.

With additional reference to FIG. 2, it will be seen that the treatment zone 20 is defined in part by spaced opposed wall members 44a and 44b. The wall members 44a and 44b lie in non-parallel planes which converge at an underlying location exterior of the treatment zone 20, which location preferably coincides with an elongated horizontally disposed groove 46 in the upper surface of a stationary support member 48, the latter forming a part of the support means generally indicated at 24. Each of the wall members 44a and 44b is preferably formed integrally with a converging upper wall section 50 and a diverging lower wall section 52, the former being secured as by welding at 54 to the wall 56 of the treatment chamber 18, and the latter having horizontally extending flanges 58 which are again secured as by welding at 60 to another wall section 62 of the housing 16.

The support member 48 is secured in place on brackets 64 which are attached to the opposite sides of the tank 12. The reed member 22 is carried by the support member 48, with its lower edge seated in groove 46.

Support member 48 is further provided with inclined sides 66 having attached thereto retaining members 68 by means of bolts 70. The retaining members 68 are preferably provided with inwardly turned upper flanges 72. The retaining members 68 cooperate with the centrally located reed member 22 and the underlying support member 48 to define cavities on either side of the reed member 22, which cavities contain a resilient compressible packing material 74, for example silicone rubber.

During operation of the apparatus, and as described earlier in the specification, liquid is pumped from tank 12 into treatment chamber 18 and then out through the treatment zone 20. The exiting stream of liquid passing between wall members 44a and 44b causes the reed member 22 to vibrate between the extreme positions indicated in dotted at 22a and 22b in FIG. 2.

The reed member 22 vibrates about its lower edge, which is seated in groove 46. Since groove 46 is approximately coincident with the line of convergence of the planes containing wall members 44a and 44b, and since the material 26 being treated is guided over the wall members 44a and 44b, this arrangement avoids any line or edge contact between the reed member and the material being treated. Instead, the opposite sides of the upper portion of the reed member come into face to face contact with the material passing over the wall members 44a and 44b, the result being a padding action which is further cushioned by liquid momen-

tarily caught between the material and the reed member. Marking of the material being treated is thus completely avoided.

By committing the reed member 22 to vibrate about its lower edge, and by providing resilient compressible packing material 74a and 74b on the inside of the reed member, reed vibrating is accompanied by minimum bending, and hence failure due to the development of metal fatigue is for all practical purposes eliminated.

It is our intention to cover all changes and modifications of the embodiment herein chosen for purposes of disclosure which do not depart from the spirit and scope of the invention as defined by the claims appended hereto.

We claim:

1. Apparatus for subjecting moving material to a liquid treatment, comprising: a pair of spaced opposed wall members defining a treatment zone therebetween, the said wall members lying in non-parallel planes which intersect at a line which is located exterior of said zone, support means including a fixed support member having a groove therein which is coincident with said line, a flexible planar reed member having one edge seated in said groove, said reed member protruding into said zone from said support means, means for passing a stream of processing liquid through said zone, the position of said reed member in said zone being such that the flow of processing liquid will cause said reed member to pivotally vibrate about said one edge between said wall members, and guide means for directing the material being treated through said zone between said reed member and at least one of said wall members.

2. The apparatus as claimed in claim 1 wherein said support means is further characterized by retaining members extending upwardly from said support member on opposite sides of said reed member, and resilient

filler means between said retaining members and said reed member for laterally supporting said reed member.

3. Apparatus for subjecting a moving web to a liquid treatment, comprising: housing means enclosing a treatment chamber; a passageway forming a treatment zone leading from said treatment chamber to an opening at the exterior of said housing means, a portion of said treatment zone being defined by spaced opposed wall members, the said wall members lying in non-parallel planes which intersect at a location exterior of said housing means; support means at said exterior location, said support means including a support member having an elongated groove facing said opening, said groove extending along the line of intersection of said non-parallel planes; a flexible planar reed member carried by said support means, one edge of said reed member being seated in said groove, said reed member extending from said support means into said treatment zone, said support means further including resilient means on opposite sides of said reed member for laterally supporting said reed member; means for pumping processing liquid into said chamber, from whence the liquid passes through said treatment zone and out through said opening, the position of said reed member being such with respect to said wall members that the flow of processing liquid through said treatment zone causes said reed member to vibrate laterally between said wall members, and means for guiding the material being treated into and out of said treatment chamber through said treatment zone, the entering material being passed between said reed member and one of said wall members, and the exiting material being passed between said reed member and the other of said wall members.
